UNITED STATES PATENT OFFICE.

IRA H. SPENCER, OF WEST HARTFORD, CONNECTICUT, ASSIGNOR TO THE SPENCER TURBINE COMPANY, OF WEST HARTFORD, CONNECTICUT, A CORPORATION OF CONNECTICUT.

TEMPERATURE REGULATOR FOR BLOWERS.

Application filed May 21, 1919 Serial No. 298,674.

To all whom it may concern:

Be it known that I, IRA H. SPENCER, a citizen of the United States, residing in West Hartford, in the county of Hartford and State of Connecticut, have invented a new and Improved Temperature Regulator for Blowers, of which the following is a specification.

My invention relates to the class of devices employed to prevent overheating of the air supplied by blowers for various purposes, and especially for the operation of musical instruments, and an object of my invention, among others, is to provide a device of this class that shall be simple in construction and that will effectively accomplish its purpose.

One form of device embodying my invention and in the construction and use of which the objects herein set out, as well as others, may be attained, is illustrated in the accompanying drawings, in which—

Figure 1 is a view in side elevation of a blower having my improved regulator attached thereto.

Figure 2 is a view in end elevation of the same with parts broken away to show construction.

Figure 3 is a detail view, scale enlarged, illustrating the construction of the temperature actuating device for controlling one of the valves.

Figure 4 is a detail view illustrating the construction of the pressure operating device for controlling another of the valves.

In the operation of blowers, for supplying air for various purposes, the conditions are such as to generate more or less heat depending upon the amount of pressure, the greater the pressure the greater the heat, and the temperature often rises so high as to be injurious to devices to which the air is supplied. This is especially true in the operation of multi-stage fan blowers employed for supplying air to musical instruments, and while my invention is not limited to a blower for any special purpose, yet as it finds ready adaption in connection with that type of blowers above mentioned employed for the purpose stated, I have selected such a blower for the purpose of illustrating my invention in the drawings forming a part of this application, in which drawings the numeral 5 indicates a case of

a blower of the multi-stage type, the series 55 of fans not being specifically illustrated but the arrangement of which is well understood by those skilled in the art. These fans are mounted upon a shaft 6 rotated as by means of a motor 7. Said case has an inlet opening 8 at one end and an outlet pipe 9 extending from an outlet opening at the end of the case opposite said inlet. It will be understood that the pipe 9 extends to or communicates with a passage leading to the 60 musical instrument or other device that is supplied with air, which air may be retained in a reservoir or other suitable receptacle or otherwise disposed of in connection with the instrument in any well known manner. 70

In order to prevent the heating of the air to an objectionable extent, as hereinbefore referred to, I provide means for saturating the air with moisture, as with water, supplied at the inlet end of the case, the water 75 being introduced in the form of a spray from a nozzle 10 at the end of a water pipe 11 leading from any suitable source of supply and having a manually operated valve 12 by means of which the water or other liquid may be effectually shut off. As a means for automatically controlling the supply of water or other liquid to regulate the temperature of the air, I provide a temperature regulated valve 13 of any suitable 80 construction, the specific arrangement of such valve being omitted herein but which valve will be of any suitable well known type embodying a plunger 14 for its operation. A stem 15 of an expandable valve actuator 16 is operatively connected with the plunger 14, in the structure herein shown the ends of the plunger and stem abutting one against the other. The actuator herein shown is of the "bellows" type, a tube 17 leading thereto from a thermostat 18 located in the outlet pipe 9. This thermostat 85 may be of any desired construction, the form herein shown comprising a shell filled with any suitable material responding to the effects of heat, ether satisfactorily answering the purpose.

In the operation of the device thus far described, the pipe 11 being open to the valve 13, and the blower being in operation, as the pressure of the air is raised the temperature will be correspondingly raised. This raising of temperature of the air will

expand the ether within the thermostat 18, the tube 17 and the actuator 16, dis- tending the latter and forcing the stem 15 against the plunger 14 to effect open- ing movement of the valve. This will in- troduce a spray of water or other liquid to the air passing into the blower and the air being thus saturated will be reduced in temperature as it passes into the outlet 10 pipe 9, and the amount of water or other liquid supplied to this air will be nicely graduated according to the degree of tem- perature existing in or around the thermo- stat 18.

15 It will be understood that the operation of the blower may be automatically regu- lated in a common and well known manner to supply only such air as may be required in the device supplied with air from the blower.

20 It should, therefore, be noted that in case the operation of the blower ceases, the tem- perature at the thermostat 18 will continue for some time thereafter and the valve 13 will, therefore, remain open and this supply 25 of water within the case 5 not being carried off by the air, after the blower ceases its operation, would become objectionable as the case would be flooded.

To overcome this result I provide a pres- 30 sure regulated valve 19 of any suitable and well known form (the specific construction not being shown herein) embodying a stem 20. This stem is connected with a diaphragm 21 located in a shell 22 communicating by 35 a passage 23 with the interior of the out- let pipe 9, said shell being attached to said outlet as by means of legs 24 and prefer- ably in proximity to the case 5. A valve 40 operating spring 25 is located in a neck 26 extending from the shell 22, one end of the spring thrusting against the end of said neck and the other end of the spring 45 thrusting against the diaphragm 21, there- by operating to close the valve.

The operation of this part of my im- 50 proved device automatically effects supply of water, depending upon the amount of pressure within the shell 22. When the blower is started to supply air for the pur- 55 pose intended, as soon as the pressure is raised to the proper extent, such pressure will affect the diaphragm 21 and the latter will operate the stem 20 to open the valve 19. Water will not, however, enter the 60 blower for the reason that the valve 13 is closed. As soon as the temperature rises to a certain degree the thermostat 18 will effect opening movement of the valve 13 and the water will be supplied in this way to 65 the air passing into the blower. During the operation of the blower the temperature of the air will be regulated and kept at the proper degree. Just as soon as enough air is supplied and the blower stops its opera- 70 tion the lowering of the pressure caused by the blower ceasing its operation will effect closing movement of the valve 19 and prevent flooding of the blower.

The supply of moisture to the air serves another useful purpose, in that the air supplied to the musical instrument is not only kept at a desirable temperature but it is also moistened to such extent that undue dryness will not be caused to parts of which the musical instrument is composed.

In accordance with the provisions of the patent statutes, I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A device for effecting flow of air, including means for supplying a temperature changing medium to a volume of air acted upon by said device, a plurality of inde- 90 pendently operable valves for regulating a single delivery of said temperature chang- ing medium, and means acting independ- 95 ently each of the other and actuated by reason of different conditions existing in said volume of air to operate said valves.

2. A device for effecting flow of air, in- cluding means for supplying a temperature changing medium to a volume of air acted upon by said device, a plurality of valves 100 for regulating a single supply of said tem- perature changing medium, means affected by temperature conditions in said volume of air for operating one of said valves, and means affected by pressure conditions in said 105 volume of air for operating another of said valves.

3. A device for effecting the flow of air including an inclosing case, means for sup- 110 plying a temperature changing medium to a volume of air within said case, a plurality of independently operable valves for regu- lating a single delivery of said temperature changing medium, and independently oper- 115 able regulators operatively connected with each of said valves and located in proxim- ity to the outlet from said case, said regula- 120 tors being operated by reason of different pressure and temperature conditions exist- 125 ing in the air flowing through said outlet.

4. A device for effecting flow of air in- cluding an inclosing case, a pipe connected to supply a temperature changing medium to said case on the inlet side thereof, a con- 130 duct for flow of air connected to said case at the outlet side thereof, a plurality of in- dependently operable valves located in said pipe, and controllers located in said conduit and each connected with one of said valves, said controllers being actuated by different

pressure and temperature conditions as to the air flowing through said conduit.

5. A device for effecting flow of air including an inclosing case, a pipe connected with said case to conduct a temperature changing medium thereto on one side thereof, a conduit connected to said case to conduct flow of air to the opposite side thereof, a plurality of valves located in said 10 pipe, a pressure operated controller located in said conduit and operatively connected with one of said valves, and an independently operable temperature affected controller located in said conduit and operatively connected with the other of said valves.
6. A device for effecting the flow of air including an enclosing case, means for supplying a cooling medium to a volume of air created by said device, a main valve to control flow of said cooling medium, means operated by the air pressure within the case to operate said main valve, a secondary valve to control the flow of said cooling medium and means actuated by the temperature of the air flowing from enclosing 25 case to operate said secondary valve.

7. A device for effecting the flow of air

including an inclosing case, means for supplying a cooling medium to a volume of air created by said device, including a supply pipe entering the case, a pair of independently operable normally closed valves in the pipe, one of the valves being pressure operated by the flow of air passing from the case to permit the flow of cooling medium to the other valve, and the other valve being temperature controlled in its operation to discharge the cooling medium into the case.

8. A device for effecting the flow of air including an inclosing case, means for supplying a cooling medium to a volume of air created by said device, including a supply pipe entering the case, a pair of independently operable normally closed valves in the pipe, one of the valves being automatically operated by air pressure upon starting and stopping the device to permit the flow of cooling medium to the other valve, and the other valve being temperature controlled in 45 its operation to discharge the cooling medium into the case.

IRA H. SPENCER.
